UNITED STATES PATENT OFFICE

171,666

DINNER PLATE

Evan K. Shaw, Manhattan Beach, Robert Y. Allen, Pacific Palisades, and Melvin Shaw, Beverly Hills, Calif., assignors to Metlox Mfg. Co., Manhattan Beach, Calif., a corporation of California

Application December 2, 1952, Serial No. 22,516

Term of patent 14 years

(Cl. D44—15)

To all whom it may concern:

Be it known that we, Evan K. Shaw, Robert Y. Allen and Melvin Shaw, all citizens of the United States of America, residing at Manhattan Beach, Pacific Palisades, and Beverly Hills, in the county of Los Angeles, State of California, respectively, have invented a new, original, and ornamental Design for a Dinner Plate, of which the following is a specification, reference being had to the accompanying drawing forming a part thereof.

The figure is a top plan view of a dinner plate showing our new design.

The shape of the dinner plate is of a conventional configuration viewed from the side or bottom thereof.

We claim:

The ornamental design for a dinner plate, as shown and described.

EVAN K. SHAW.
ROBERT Y. ALLEN.
MELVIN SHAW.
